EYEGLASS FRAME OR THE LIKE

Alexander Kono, Woodside, N.Y., assignor to Kono Manufacturing Co., Inc., New York, N.Y., a corporation of New York

Filed Sept. 20, 1966, Ser. No. 3,929

Term of patent 14 years

(Cl. D57—1)

FIG. 1 is a perspective view of an eyeglass frame or the like showing my new design;

FIG. 2 is a front view thereof;

FIG. 3 is a side view thereof; and

FIG. 4 is a top view thereof.

My design for the eyeglass frame disclosed is characterized by the beveled top portion of the said frame having a segment-like appearance consisting of an arcuate top surface and a straight line bottom surface as shown.

I claim:

The ornamental design for an eyeglass frame or the like, substantially as shown and described.
